MATERNITY GARMENT

Janet Briggs, Chicago, Ill., now by change of
name Jeanette M. Troxell

Application October 9, 1947, Serial No. 778,802

26 Claims. (Cl. 2—74)

1

My invention relates generally to maternity garments and, more particularly, to maternity garments which permit the wearer selectively to increase the convexity or fullness of the garment at the desired level in the front throughout the entire period of pregnancy.

Maternity garments presently on the market appear to be devoted exclusively to providing expansion of the garment circumferentially, in an amount governed by the wearer, as the period of pregnancy progresses. The ability to enlarge circumferentially is most commonly achieved by forming the garment with a circumference corresponding to the maximum circumferential increase expected in the wearer and then employing a draw string construction by means of which the garment may initially be constricted at the waist to a normal waist measurement and may subsequently be "let out" at the waist selective amounts to accommodate the increase in girth of the wearer. Although a construction allowing circumferential enlargement is necessary, it fails to take into consideration that the expansion is not only circumferential but also produces an increase in the vertical dimension of the pregnant woman as measured from the waist over the enlarging abdomen to the hem line. As a consequence, the present forms of maternity garments rise up at the front as the abdomen of the wearer enlarges and the resulting irregular hem line is very unpleasing in appearance. The hem line in the front may rise as much as four to six inches during the entire period of pregnancy and previous attempts to allow for this have been inadequate and have resulted in constructions which are unpleasing in appearance and uncomfortable to the wearer.

It is a primary object of my invention to provide a maternity garment which will fit the curvature of the figure not only in the very early stages of pregnancy when the figure is substantially normal but also to give a stylish appearance all through the term of pregnancy. In accomplishing this objective there is provided a garment which will permit the wearer to increase the fullness of the front of the garment, that is, to provide a convexity to accommodate the enlarging abdomen and thereby to increase the total vertical measurement of the front in order to maintain the hem line of the garment even at all times. Means for allowing a selective amount of circumferential enlargement of the garment is also incorporated. The resulting garment is pleasing in appearance and is comfortable to the wearer.

2

It is a further object of my invention to provide means for increasing the convexity of the garment at the level where it is most needed by the individual wearer, since the level of the greatest enlargement of the abdomen varies in different women and may also vary in the same women during the period of pregnancy or during subsequent pregnancies. Generally the greatest forward projection of the abdomen will occur several inches below the waist level and consequently in the various forms of the maternity garment of my invention I provide means for increasing the convexity of the garment at that level. The means for increasing the convexity may be described, briefly, as a double layer of material extending horizontally across the front of the garment and held at the side seams, together with one or more lines of spaced apart stitches extending horizontally from seam to seam in the double layer. When there are a plurality of lines of stitches they may be successively ripped out to provide increasing convexity and length in controllable degrees.

Since the woman's body in the area of the waistline increases considerably, measured both circumferentially and vertically, as the term of pregnancy progresses, there is also provided means for increasing the fullness or convexity of the garment at the waist level. Normally the bust enlarges as the period of pregnancy progresses and therefore there is also provided means for increasing the fullness and vertical measurement of the bodice of the maternity garment.

Heretofore not too much consideration appears to have been given to designing maternity garments which are pleasing in appearance, the primary concern of most manufacturers appearing to be that of merely allowing an increase in the circumference of the garment without any attempt to conceal or minimize the ungainly appearance of the wearer or to provide more esthetic lines to the wearer by the design of the garment. It is a particular advantage of my invention that the means for increasing the convexity and length of the front of the garment lends itself to many attractive designs and decorative effects.

In one form of my invention I provide a maternity garment which is adapted to be employed in conjunction with a loose fitting outer garment, such as a smock, whereby the actual silhouette of the wearer may be concealed. In the accomplishment of this objective I provide in the garment, which is covered by the smock, an upper

front portion which is circumferentially expandible and which extends from the shoulder line to a level below the abdomen and a lower front skirt portion which is non-expansible, the lower skirt portion in conjunction with the back skirt portion having a circumference corresponding to that of a normal dress. The upper front portion includes means for increasing the convexity of the garment, said upper portion being covered by the smock or some other form of full, loose-hanging garment which normally conceals the true silhouette of any wearer, pregnant or not. When the usual form of maternity garment is worn beneath a smock, the greatly increased circumference of the garment at the hem reveals to any observer that the wearer is pregnant even though the lines of the smock tend to conceal the enlarged abdomen. Since the depending skirt portion of the garment of my invention does not increase in circumference as pregnancy progresses, as the hem line of the usual maternity garment is required to do, the combination of the maternity garment and the smock conceals the fact that the wearer is enlarging through the abdomen. As the abdomen increases in size the upper front portion of the maternity garment is adapted to provide increased convexity or fullness but the hem of the skirt remains the same in circumference and to all outward appearances an observer is unable to determine that a condition of pregnancy exists. Since the overlying garment, such as a smock or tunic, is in common use, it can be purchased in a variety of colors and attractive designs so that the pregnant woman may provide a varied wardrobe for herself.

In the usual construction of a dress, the block for the bodice and the block for the skirt are cut along inwardly curved lines along those edges which will be joined together. This results in the cutting out of a portion of the material from each block in order to provide a garment which will properly fit the waist of the wearer since the waist is of a smaller dimension than the dimensions of the hip, below the waist, and the upper portion of the body, above the waist. It is another object of my invention to provide a maternity garment which will be constructed without the cutting out of a portion of the front of the garment, such as is done to form the waistline in dresses, so that this added material may be employed to increase the convexity and the vertical measurement of the garment when such increase in vertical length is required by the enlarging abdomen of the wearer as pregnancy progresses.

In attaining the objective there is provided in one form of the invention a single piece of material in the front extending from the shoulder level to a level below the abdomen, along with means for constricting the waist of the garment so that it will fit the wearer neatly during the earlier period of pregnancy. This construction provides added material from which increased length of the front of the garment is obtainable as needed. The method of releasing this additional material will be described hereinafter.

In another form of the invention I provide a maternity garment having a front portion formed of a plurality of pieces, such as a bodice and a skirt, which pieces are cut with the grain of the goods at those edges which are to be joined together, instead of cutting the adjoining edges along a line curved inwardly of each portion. The material thus gained by not cutting along this curved line is usable during the latter stages

of pregnancy as the waist and abdomen enlarge. Initially the waistline of my maternity garment is adapted to fit the normal figure by reason of the novel manner in which the bodice portion and skirt portion are joined together, namely, by a plurality of lines of stitches which extend generally horizontally across the front of the garment from side seam to side seam, the deepest line of stitching constituting the normal waistline and subsequent lines of stitching of progressively decreasing curvature being provided so that the wearer may selectively rip out successive lines of stitches in order to accommodate the increasing convexity of the waist and upper portion of the abdomen.

In one form of my invention the means for providing convexity to the front of the garment to accommodate the enlarging abdomen is provided by means of a tuck extending horizontally across the garment from side seam to side seam, said tuck being fixed at the side seams but being releasable intermediate said seams so that it changes from a tuck to a pair of darts extending from the respective side seams.

In a modification of the means for producing convexity or fullness, as described in the preceding paragraph, there is provided in the folded portion of the tuck a plurality of lines of stitches extending, in spaced relation to each other, from side seam to side seam with the line of stitches forming the tuck and the lines of stitches in the folded portion being successively releasable by the wearer to provide convexity to the garment in controllable degrees.

In order that the desired enlargement of the garment may be provided at the place where it is most needed by the individual wearer, the garment is provided with a plurality of such releasable means so that the wearer may select the releasable means best adapted to provide convexity where needed, in accordance with the particular shape of her body at that particular time.

So that the wearer will not rip out lines of stitches which hold the garment together at the seams I prefer to employ a means of designating those lines of stitches which are releasable from those lines of stitches which are not to be released. This may be done in a variety of ways, for example, by a different colored thread for forming the releasable stitches, by employing a different type of stitching for the releasable lines of stitches, by labels or printed marks on the inner side of the garment which are associated with the lines of stitches which are to be removable, or by other means. For convenience and ease of manufacture I have found it very satisfactory to employ thread of a different color to indicate those lines of stitches which are removable and to indicate the extent to which the stitches are to be released.

When the releasable means for the garment are incorporated on the surface of the garment which will be exposed to the view of others it is, of course, desirable that the lines of stitches be concealed so far as they are functional and to permit those only to be viewed which are decorative. To attain this object the garment of my invention may be provided with releasable means which are concealed from the outer surface of the garment but which are readily releasable by the wearer as desired. The various constructions by which the releasable means are concealable will be set forth more fully in the detailed description hereinafter and it will there become apparent

that they may be of different forms and may be employed at various levels of the garment so that the wearer will be able to employ releasable means at any and all levels at which convexity or fullness is required by the enlarging of the body, whether at the bust, waist or abdomen level or at a level adjacent thereto.

It should be noted that in providing the releasable means the horizontal grain of the goods is maintained substantially level at all times, both at that stage when the figure is still in its normal shape and also at the latest stage of pregnancy, when the releasable means have been employed to add convexity and additional vertical length to the front of the garment. This is important, since any construction which results in a distortion or twisting of the grain of the goods out of the horizontal will always give a noticeable and unsightly appearance to the garment. Such condition is even more apparent in a maternity garment than it would be in a normal garment.

Other objects, uses and advantages of my invention will become apparent from the following detailed description and claims, when taken with the accompanying drawings in which:

Figure 1 is a side elevation of a maternity garment embodying my invention, the wearer thereof being at the earliest stages of pregnancy when the figure is of a substantially normal shape;

Figure 2 is a side elevation of the garment illustrated in Figure 1 with the wearer being shown in an advanced state of pregnancy, a covering garment such as a smock being indicated in dotted lines;

Figure 3 is a fragmentary perspective view on enlarged scale of the front of the garment illustrated in Figure 2;

Figure 4 is an enlarged, fragmentary perspective view of the front of the garment with the section being taken substantially on the line 4—4 of Figure 1;

Figure 5 is an enlarged fragmentary perspective view of the front of the garment with the section being taken substantially on the line 5—5 of Figure 2;

Figure 6 is a view similar to that of Figure 4 showing a modified form of limiting means for controlling the extent to which the lines of stitches may be ripped out;

Figure 7 is a view similar to that of Figure 5 and embodying the modified limiting means of Figure 6;

Figure 8 is a fragmentary perspective view showing the back, or reverse, side of the front portion of a garment embodying a modified form of releasable means, with the garment being turned inside out for purposes of illustration;

Figure 9 is a sectional view taken substantially on the line 9—9 of Figure 8;

Figure 10 is a front elevation of another form of maternity garment embodying my invention with the wearer being shown in the earliest stage of pregnancy when the figure is of a substantially normal shape;

Figure 11 is a side elevation of the garment of Figure 10 with the wearer being shown in an advanced stage of pregnancy;

Figure 12 is an enlarged, fragmentary perspective view of the front of the garment with the section being taken substantially on the line 12—12 of Figure 10;

Figure 13 is an enlarged, fragmentary, perspective view of the front of the garment with

the section being taken substantially along the line 13—13 of Figure 10;

Figure 14 is an enlarged, fragmentary, perspective view of the portions of the garment illustrated in Figure 13 showing the manner in which they are initially secured together;

Figure 15 is an enlarged, fragmentary, perspective view of the front of the garment with the section being taken substantially on the line 15—15 of Figure 10; and

Figure 16 illustrates another form of maternity garment embodying my invention.

Referring first to Figures 1 through 5 there will be seen a maternity garment, indicated generally by the reference numeral 1, which comprises a back portion 3 and a front portion 5 secured to the back 3 along side seams such as the side seam 7. The upper portion 8 of back 3 or portions 9 and 13 of skirt 15 may be formed of any desired number of pieces. However, the skirt 15 may be formed of a different material of finer quality than the upper portion of the garment which extends upwardly from the line A—A in Figure 1. The front comprises an upper portion 11 and a depending skirt portion 13, the upper portion 11 of the garment being formed of a material such as the upper portion 8 of the back 3, and the skirt portion 13 of the front 5 being formed of the same type of material as the skirt portion 9 of the back 3. The upper front portion 11 is initially constructed so that it, together with the upper back portion, will have a maximum circumference corresponding to the maximum enlargement, circumferentially, which the wearer will attain during the period of pregnancy. Means 17, for constricting the garment at the waist so that it will fit the figure during the earlier part of pregnancy when the figure is substantially normal, may take many forms but is shown in Figure 1 in the form of a drawstring 19 carried in a guide 21 in the front 5 of the garment 1. It will therefore be seen that the upper front portion 11 of the garment 1 is circumferentially expandable in amounts selected by the wearer in order to accommodate the enlarging abdomen.

The upper front portion 11 of front 5 is cut with such fullness that its lower edge is much wider than the adjoining edge of the skirt portion 13 and the two portions are therefore secured together along their adjacent edges for their respective full lengths by gathering the lower edge of the upper front portion 11 to the upper edge of the front skirt portion 13. It is to be particularly noted that the depending skirt, indicated generally by the reference numeral 15, is not circumferentially expandable but instead maintains the same circumference at all times throughout the period of pregnancy. The purpose of this will now be explained.

During pregnancy a woman may feel extremely self-conscious because of the change in shape of her figure and consequently would prefer, if possible, to be so clothed that her condition of pregnancy would not be readily observable. Maternity garments presently on the market reveal a condition of pregnancy in two very noticeable manners, first, by the enlarged abdomen of the wearer which extends the front of the garment and causes the hem line to rise up as much as four to six inches and, secondly, by the extensive increase in the circumference of the hem due to the fact that the garment has been permitted to expand circumferentially from the waist downwardly. By my invention I can elim-

inate both of the above mentioned indications of the pregnant condition. In the first place the depending skirt portion 13, which will be seen by others, is not permitted to enlarge circumferentially when the upper portion 11 of the front 5, which will be concealed in a manner to be described, is permitted to expand circumferentially and in other directions in order to accommodate the abdomen. In other words the hem line maintains the same circumference throughout the entire period of pregnancy while the enlarging abdomen is comfortably accommodated, by reason of the improved structure of the garment, by permitting the upper portion 11 to be expandable circumferentially to any degree necessary. It will be observed that I provide means not only for increasing the circumference of the garment in the upper front portion 11 where needed, but also I provide means for adding length and producing a convexity to the front of the garment in the upper front portion 11 since the measurement vertically from the waist along the outline of the enlarged abdomen to the hem line also increases as pregnancy progresses. This means for adding length and producing convexity, which will be described in detail immediately below, permits the wearer to maintain the hemline at the proper level throughout the period of pregnancy, thus eliminating the second factor which tends to reveal a pregnant condition.

Heretofore maternity garments have been designed mainly for the purpose of providing means for increasing the garment circumferentially. They have not however satisfied the need for an increase in the vertical measurement. The problem of covering the figure as it enlarges may be better visualized if you consider what would be necessary to cover a portion of a balloon as it is expanded. It is obvious that circumferential enlargement is only one aspect of the increase in the surface. Means must therefore be provided for not only increasing the front of the garment in a circumferential direction but also in all directions since a somewhat hemispherical surface is presented.

The means for producing a convexity or fullness to the front of the garment to accommodate the enlarging abdomen and for thereby increasing the vertical measurement of the front of the garment is indicated generally by the reference numeral 23 and it comprises, in its simplest form, a tuck which extends horizontally from one side seam 7 to the other side seam and is of the same width as it extends across the front of the garment. Consequently the horizontal grain of the goods is maintained substantially parallel to the floor throughout the front of the garment 1. If reference to Figure 4 will be made, it will be seen that in a preferred form of the invention means for providing convexity and length to the front of the garment includes in addition to the line of stitches 25, which forms the tuck, a plurality of lines of stitches 25a, 25b, 25c, 25d, 25e, in the folded portion 27 of the tuck. The tuck provides in the folded portion 27 two layers of material 29 and 31. It will be observed that the lines of stitches 25, 25a, 25b, 25c, 25d, and 25e extend substantially horizontally in spaced relation to each other from one side seam 7 to the other side seam 7 across the front 5 of the garment 1. All of the lines of stitches, including the line forming the tuck, are releasable by the wearer intermediate the side seams as desired. The lines of stitches are usually released progressively beginning with the line 25 forming the

tuck. Since the tuck is held in place by the side seams 7, even when the lines of stitches 25, 25a, 25b, etc. are released, the tuck will be converted to a pair of darts instead of being dropped the same amount from side seam to side seam.

It should be here explained that the side seams 7 do not need to lie exactly in the position indicated in Figures 1 and 2 but may be in front or in back of the central line of the side of the wearer if that is desired. In any event, the reference to side seams in this description and in the claims means those seams between which the means 23 for producing convexity is disposed. It will be understood that if vertical seams were to pass across the lines of stitches 25, 25a, 25b, etc., that would prevent those lines of stitches from being ripped out beyond such vertical lines of stitches unless the vertical lines were also ripped out. From actual experiment it has been determined that having the side seams along the center of the side of the wearer produces very satisfactory results.

As the woman enlarges during pregnancy she will release the upper front portion 11 circumferentially by means of the constricting means 17 at the waistline and will also rip out successively the lines of stitches 25, 25a, etc. As the first line of stitches 25 is ripped out the tuck is changed to a pair of small darts extending toward each other from the side seams. As successive lines of stitches 25a, 25b, etc. are ripped out, a deeper and deeper dart is provided at each side of the garment and consequently increased convexity and fullness is provided. If reference will be made to Figure 2 it will be seen that the convexity thus provided permits the upper front portion 11 of the garment to fit about the protruding abdomen and to come back under it to the upper edge of the skirt portion 13 at the front 5. As a result the skirt does not rise up in the front and produce an uneven hem line and it is permitted to be non-expansile as well. When a garment such as a smock or other loose fitting covering garment is worn over the maternity garment 1 the true shape of the wearer is entirely concealed because a smock or similar blousing garment conceals the silhouette of any person whether pregnant or not. Consequently, with a covering garment, such as the garment 32 indicated in dotted lines in Figure 2, there is nothing to indicate that the wearer is pregnant since the circumference of the hem line remains constant at all times and the depending skirt 15 remains at the same level. Since smocks and similar garments are commonly worn by women there are many varieties and designs thereof on the market, including some that are highly decorative and are worn as formal attire. As a result, the pregnant woman has available a wide selection of covering garments which she may employ in connection with the maternity garment 1.

The loose-hanging covering garment, such as the smock 32, does not have the same tendency to ride up on the abdomen as does a dress. However, I may also embody my invention in the smock, whereby it too may acquire additional vertical measurement, and convexity in the front. This may be done by the means 23 just described or in the manner described hereinafter with respect to the garment of Figures 10 and 11.

It will be apparent that the upper portion of the garment 1 from the line A—A upward may be formed of an inexpensive material since it will be covered. It is only necessary that the de-

pending skirt 15 be of a usual dress material since it alone will be observable when the covering garment is worn.

It will be recalled that the means 23 for producing convexity to the front of the garment—which means, in Figure 1, is shown as being a tuck with a plurality of parallel lines of stitches in the folded portion of the tuck—has the tuck secured at the side seams with the lines of stitches being releasable only intermediate the side seams. Even if the lines of stitches were all ripped out completely from one side seam to the other, darts would always result, as shown in Figure 3, since the tuck originally placed in the garment is not releasable at the side seams. Such darts would be similar to unpressed darts since they would not be secured against the front of the garment. Cups or pockets would therefore tend to be formed. Consequently, in a preferred form of my invention the wearer is instructed by code means, such as different colored thread or other means, to rip out the successive lines of stitches decreasing amounts in either direction from the center of the front portion 5. The darts, which are formed when the lines of stitches are ripped out in that manner, are then held flat against the front of the garment by those stitches which are permitted to remain in the various lines of stitches. The resulting darts are those illustrated in Figure 3. The various dots 33 are intended to represent the places where the stitches have been ripped out from the material. In actuality these dots or needle holes will not be visible.

So that the wearer of the garment may more easily rip out the successive lines of stitches only the proper amount, that is, decreasing amounts for the successive line of stitches, I provide, as may best be seen in Figures 4 and 5, a pair of lock stitches 35 for each line of stitches in the folded portion 27 of the tuck. The lock stitches of each pair are spaced equidistant from the center line on the front of the garment. It is then a very simple matter for the wearer to cut a line of stitches adjacent the center front of the garment and to rip it in each direction as far as the lock stitch will permit at each end of the line of stitches. It will be seen that the inner lines of stitches have their respective pairs of lock stitches 35 spaced increasingly greater distances from the side seams, i. e., closer to the vertical median line of the front 5. Consequently, when all of the lines of stitches are ripped back as far as their respective lock stitches will permit, the result will be that shown in Figure 5 and the darts 34 which will be formed adjacent each side seam will be held flat and in place by those stitches, of each line of stitches, which are not ripped out.

In place of the lock stitches 35 of Figures 4 and 5 I may substitute a single line of stitches 37 in Figures 6 and 7 which intersects each side seam and also curves through and intersects each of the lines of stitches 25a, 25b, etc. at two places. Line 25 may also be so intersected, if desired. The line of stitches 37 therefore prevents the wearer from ripping each of the lines of stitches 25a, 25b, etc., all the way to the side seams in somewhat the same manner as do the lock stitches of Figures 4 and 5. In Figure 7 there will be seen the resulting dart 34' which is held in place by the stitches which are not ripped out in the various lines of stitches when a control line of stitches 37 is employed. It will be understood that in place of such a single line of stitches 37 two separate lines of stitches, curved or straight, may be employed, each extending from

a side seam and intersecting the horizontal lines of stitches 25a, 25b, etc.

In Figures 8 and 9 I show a tuck 23 which has a straight line of stitches 25, i. e., a line following the horizontal grain of the goods, and a plurality of inner lines of stitches 25a, 25b, 25c, and 25d in the folded portion 27, all of the latter lines of stitches being curved in this modification of my invention with the lines of stitches being adapted to be ripped completely from one side seam 7 to the other side seam 7. Consequently, the wearer does not have to rely upon lock stitches or similar devices and does not need to watch exactly how far the line is ripped out since the side seams 7 will limit the ripping operation. The curved lines of stitches 25a, 25b, etc., automatically produce darts as they are successively ripped out and the darts are held in place by the lines of stitches not yet ripped out and therefore cups or pockets will not be formed. It will be appreciated that the parallel lines of stitches extending horizontally from one side seam to the other side seam are more easily and quickly formed than curved lines having different radii since they may be stitched on a multiple-needle machine, whereas the curved lines of stitches ordinarily will need to be formed individually one after the other. A garment having the straight parallel lines is therefore more economical to produce.

It will be observed from Figures 1 and 2 that the means 23 for producing a convexity and fullness to the garment is situated at that level at which the wearer will have the greatest forward projection during pregnancy. It will be understood that several such means 23, for example, tucks, may be employed at different levels on the front portion 5 of the garment 1 and that they may be wider or narrower, that is, of greater or lesser vertical measurement, than the tucks illustrated in Figures 1 through 7. With such a plurality of tucks various shapes of figures may be accommodated since some women carry the fetus lower than do others. Consequently, I may form the garment with a plurality of tucks intermediate the waistline and the seam which joins the upper front portion 11 with the lower front skirt portion 13. However, for most women the greatest forward projection during pregnancy will be at that level indicated by the tuck 23 in Figures 1 and 2. As will be pointed out below, tucks or other means for increasing the convexity or fullness of the front of the garment may also be employed at the waist level and above the waist level, as well as below.

It will be observed that the upper front portion 11 of the garment 1 of Figures 1 and 2 extends from the shoulder level to a level below the abdomen and, although I may form this of a plurality of pieces of material, in one form of my invention I form it of a single piece of material and thereby gain additional length since there is no cutting out of the material at the waistline as is ordinarily done in the block constituting the bodice and in the block constituting the skirt portion of the front of the garment. The normal front blocks of the bodice and skirt portions of a dress have the adjacent edges, which are to be joined, cut inwardly of each block in order to fit the garment at the waist. This, however, results in the loss of some of the material which might well go into the vertical measurement of the garment to assist in maintaining the hem line level in a maternity garment. Prior to the time when the additional material is needed for

increase of the vertical measurement, it forms a slight blouse above the waistline.

In employing a one-piece upper front portion 11 I provide a proper fit at the waist while the figure still retains its normal shape by reason of the drawstring arrangement 17 or by providing a belt or waist band having a series of circumferentially spaced releasable snaps at the waist level across the front of the garment with the fullness at the front of the garment being formed in pleats somewhat in the manner illustrated in Figure 10 which will be described at greater length hereinafter. The successive snaps permit the release of the pleated fullness at the election of the wearer. In addition to providing additional vertical measurement to the front of the garment, cutting the upper front portion 11 in one piece eliminates certain steps which are ordinarily taken in the manufacture of a garment. Such construction therefore provides a reduction in the amount of labor necessary and lowers the ultimate cost of the garment.

Referring now to Figure 10 there will be seen a maternity garment 51 in the form of an outer garment which lends itself to a variety of designs and decorative effects but which also includes means for producing convexity or fullness of the garment to the extent desired as the figure enlarges. In this garment there is illustrated a plurality of tucks 53 below the waistline which extend substantially horizontally from one side seam to the other side seam and also a tuck 55 at the level of the bust in the upper front portion of the garment 51. At the waist there is provided an additional means 57 for the further addition of fullness and vertical measurement to the front of the garment, as will be explained more fully below.

It is important in an outer garment, such as garment 51, that the various means for producing convexity or fullness in the garment have their releasable portions concealed so that a pleasing appearance of the garment may be provided and so that there is no change in design as the releasable portions are employed during the term of pregnancy.

In Figure 15 there is illustrated on an enlarged scale the plurality of tucks 53 behind which are formed a plurality of smaller tucks 59 which also extend horizontally from one side seam to the other side seam behind the larger tucks 53. In the folded portion 61 of each of the smaller concealed tucks 59 there are a plurality of lines of stitches 65 which may extend parallel to each other and to the line of stitches 63 which form the smaller tuck 59. It will be understood that lock stitches may be employed in these lines of stitches 65 in substantially the same manner as that illustrated in Figures 4 and 5. If preferred, a line of stitches, such as the line 37 of Figures 6 and 7, may be employed for intersecting the parallel lines of stitches 65. From Figures 10 and 15 it will be apparent that as the successive lines of stitches 63 and 65 are ripped out in the smaller tucks 59, which are concealed behind the larger tucks 53, it will be possible to remove equal numbers of lines of stitches from each of the tucks 59 and thereby to maintain an even and balanced appearance to the large tucks 53. Alternatively, the wearer may rip out, successively, all of the lines of stitches in one tuck 59 before any lines are ripped out of the other tucks 59. It will be apparent that the lines of stitches of the various tucks may be ripped out sequentially in a variety of ways to suit the wearer's figure.

If reference will now be made to Figures 10, 11, and 12 it will be seen that I have formed the bodice 64 of the garment 51 of two portions of material 65 and 67, respectively, and that I have provided behind the tuck or folded portion 55 a smaller concealed tuck 71, tuck 71 being formed in the upper part or margin of the lower portion 67 of the bodice 64 by the line of stitches 73. In the folded portion 74 of the tuck there are a plurality of lines of stitches 75 all of which lines extend from side seam to side seam in the front of the garment 51, if the bodice is not divided vertically, or from the side seams toward the seams in the adjacent edges, if the bodice is divided vertically as at 76. The lines of stitches 75 which are formed in the folded portion 74 of the tuck 55 may take any one of the forms illustrated and described above in Figures 4, 6 or 8. Since the bust normally enlarges during pregnancy, additional fullness to the garment at the level of the bust will be provided by the tuck 71 and the releasable lines of stitches 73 and 75. When the front of the bodice 64 is formed of two portions 65 and 67, as illustrated in Figures 10, 11 and 12, greater circumferential fullness may be provided in forming the lower portion 67 without compelling unneeded fullness to be employed in the upper portion 65 which fits the shoulders of the wearer. The additional circumferential fullness of the lower portion 67 of the bodice 64 may be accommodated in a pleasing manner by shirring or pleats or by other known means. However, it is not to be overlooked that the front of the bodice may be formed of a greater or lesser number of pieces of material while yet incorporating means for providing convexity or added vertical measurement.

Referring now more particularly to Figures 10, 11, 13 and 14, it will be seen that a modified form 40 of means for providing increased fullness to the garment and for adding to the vertical measurement thereof in the front may be provided at a seam. Keeping in mind that the normal blocks 45 of the bodice and front skirt portions of the usual dress are cut inwardly along a curved line at their adjacent edges so that the garment when sewed together will fit the waist, it will be seen that I gain additional material for adding to the front of the garment by cutting the adjacent edges of the blocks for the bodice 64 and the skirt 79 with the grain of the goods and then securing the adjacent edges together by a plurality of lines of stitches 81 (each of which might be called a seam), the deepest of which lines corresponds to the normal curve of the waist line. When I say the deepest line of stitches I refer to the line which is farthest removed from the edges of the bodice 64 and skirt 79 which are joined together. Lines of stitches inwardly thereof, that is, closer to the edges which are joined together, are less and less curved and the innermost 83, that is the shallowest, is stitched with the horizontal grain of the goods. Instead of having the curved lines of stitches coming to a common point, they may be additionally spaced from each other without changing their respective curvatures as shown in Figure 13. In such construction each line intersects the side seams at points spaced from the points of intersection of the other lines with the side seams. This feature furnishes a means for providing the greatest possible additional length at center front of the garment, but it creates the smallest possible pick-up, or dart, at the side seams. The aforementioned problem of hiding the functional tuck

or seam from view under a larger tuck or belt, which constitute the style of the garment, has then been solved.

As the figure enlarges at the waist not only circumferentially but also in all directions, successive lines of stitches 81, beginning with the deepest, are ripped out, except for the final line of stitches 83 which forms a seam for holding the bodice portion 64 and skirt portion 79 of the garment together. The additional length gained by ripping out the successive lines may by itself, or in combination with small tucks 59 behind large tucks 53 (Figure 15), permit the garment to maintain an even hem line so that the garment does not rise or hike up by reason of the enlarging abdomen of the wearer. It will be understood, of course, that if the material forming the front is not divided at the waist, a releasable tuck could be employed.

To accommodate the circumferential enlargement of the figure at the waist and abdomen, the front skirt portion 79 and the bodice portion 64 are cut with sufficient circumferential fullness to accommodate the figure of the wearer at the most advanced stage of pregnancy and the additional material may be taken up circumferentially by the draw-string arrangement illustrated in Figures 1 and 2 or by providing a plurality of folds or pleats 85 in a decorative manner at the front of the garment with a belt 87 circumferentially enlargeable.

Even though I may provide a plurality of horizontally extending tucks, such as tucks 53, or a single tuck, at other levels on the front of the dress, I prefer to have at least one of the tucks at that level at which the wearer will have the greatest forward projection during pregnancy since increased convexity will be necessary at that location or immediately above that level.

Instead of a plurality of tucks such as tucks 53 in Figures 10 and 11 it is also possible to provide selective means for increasing the convexity or fullness of a garment by means of horizontal seams 91 (see the garment 89 of Figure 16) which have a plurality of curved lines of stitches (or other "seams") 93 in spaced relation to each other. A series of seams formed by curved lines of stitches was employed, as will be recalled, at the waist of the garment 51 of Figure 10. However, in the seams 93 of the garment 89 of Figure 16 the first, or deepest, line of stitches 91 which is releasable will be a substantially straight line, i. e., with the horizontal grain of the goods, since it will be desirable to have the dress initially formed with the grain of goods horizontal in all portions of the garment below and above the waist. The straight line of stitches 91 will, therefore, be the deepest line, or deepest seam, and the successive lines of stitches or seams 93 will be curved, the outermost, or shallowest, having the shortest radius of curvature. This is just the reverse of the showing in Figures 13 and 14 but achieves the same end in that it permits the greatest possible vertical increase without creating a dart at each of the side seams. It could then be used with or without a covering tuck on the outer surface of the garment. When these lines of stitches are ripped out to produce convexity or fullness of the garment at the level desired there will, of course, always be left intact one line of stitches 93 so that the pieces of the garment will not separate.

In order that the wearer may more readily determine which of the stitches of the garment are to be ripped out and which are never to be

ripped out I prefer to have the releasable lines of stitches of a different color than those which are employed to secure the pieces of the garment together. No accidents will then result and the wearer may always be able to see which lines of stitches may be safely released. Various other manners of distinguishing between the lines of stitches which are to be releasable and those which are not may be employed, such, for example, as stitches of an obviously different type, or stitches which are marked by tags or attached threads of different colors or by printing on the inner side of the garment.

While I have shown preferred embodiments of my invention, I do not intend to be limited thereto, except insofar as the claims are so limited, since modifications and other uses will suggest themselves to those skilled in the art, in view of the foregoing disclosure, without departing from the true scope of the invention as defined in the appended claims.

I claim:

1. A maternity garment comprising in combination, a back, and a front having at least a portion which is circumferentially expansible at least at the areas of the waist and abdomen, said front portion being joined to the back along side seams, and said front portion including separate vertically releasable means extending from side seam to side seam at all times at substantially different horizontal levels for the purpose of selectively increasing fullness in the front at a level at which the user's body will increase its forward projection during pregnancy.

2. The combination of claim 1 wherein the separate releasable means include a tuck extending between the side seams at the abdominal area and being releasable intermediate said seams and a horizontally extending seam at the waist level formed by a plurality of spaced apart lines of stitches extending between the side seams, the deeper lines of stitches in said tuck being spaced apart and being releasable intermediate said side seams.

3. The combination of claim 1 wherein the separate releasable means include a releasable tuck extending horizontally from one side seam to the other side seam substantially at the level of the bust, a releasable tuck extending horizontally from one side seam to the other side seam substantially at the level at which the wearer will have the greatest forward projection during pregnancy, each of said tucks including one or more lines of stitches in a folded portion of the tuck, said lines of stitches being spaced apart and extending from side seam to side seam and said lines of stitches holding together the overlapped portions of material forming the tuck and being releasable intermediate said seams, and a releasable seam in said front portion at the waist level, said seam being formed by a plurality of lines of stitches spaced apart from said other lines of stitches in said tucks and extending from side seam to side seam, the deeper lines of stitches of said seam at the waist level being releasable between the side seams.

4. In a maternity garment, in combination, a back, a front having at least a portion which is circumferentially expansible at least at the areas of the waist and abdomen, said front portion being joined to the back at side seams, and said front portion having a tuck extending horizontally from side seam to side seam at that area where the user's body will increase its forward projection during pregnancy, with said tuck be-

ing of substantially the same vertical measurement throughout, and a plurality of spaced apart horizontally extending lines of stitches one of which lines forms said tuck and the rest of which lines of stitches extend horizontally in the folded portion of the tuck inwardly of said line of stitches forming said tuck, all of said lines of stitches holding together the overlapped portions of the material forming the tuck and being successively releasable in order to provide convexity to the front of the garment, means associated with at least some of said lines of stitches on either side of the center of the front to differentially limit the extent to which said lines of stitches may be releasable along their length from the center of the front toward the side seams.

5. In a maternity garment, in combination, a back, a front having at least a portion which is circumferentially expandable at least at the areas of the waist and abdomen, said front portion being joined to the back at side seams, and said front portion having a tuck extending horizontally from side seam to side seam at that area where the user's body will increase its forward projection during pregnancy, with said tuck being of substantially the same vertical measurement throughout, and a plurality of spaced apart horizontally extending lines of stitches one of which lines forms said tuck and the rest of which lines of stitches extend horizontally in the folded portion of the tuck inwardly of the line of stitches forming said tuck, all of said lines of stitches holding together the overlapped portions of the double layer of material and being successively releasable in order to provide convexity to the front of the garment, a pair of spaced apart lock stitches formed in each of the line of stitches which are positioned inwardly of the line of stitches forming said tuck, the lock stitches of each pair being equally spaced from their respective side seams and the lock stitches of the inner lines of stitches being successively farther from their respective side seams.

6. A maternity garment comprising, in combination, a back, a front joined to the back at side seams, said front being formed of two portions which are joined together and comprise a one piece upper portion which is circumferentially expandable at least at the areas of the waist and abdomen and a lower portion non-expandable circumferentially, said upper portion being adapted to extend below the abdomen, and releasable layers of material forming a tuck incorporated in said upper portion and vertically spaced below said area of the waist for providing convexity to the upper portion of the front of the garment said layers of material being horizontally disposed and being releasable vertically at a level at which the user's body will increase its forward projection during pregnancy.

7. A maternity garment comprising, in combination, a back, a front joined to the back at side seams, said front being formed of two portions which are joined together and comprise an upper portion circumferentially expandable at least at the areas of the waist and abdomen and a lower portion non-expandable circumferentially, releasable means for circumferentially constricting the upper portion substantially at the waist level, said upper portion being adapted to extend below the abdomen and being gathered on to the upper edge of said lower portion, and a horizontally extending tuck in the upper portion between said area of the waist

and the upper edge of said lower portion at a level at which the user's body will increase its forward projection during pregnancy, said tuck being releasable.

5. A maternity garment comprising, a combination, a back, a front having at least a portion which is circumferentially expandable at least at the areas of the waist and abdomen, said front portion being joined to the back at side seams, and means for controlling the circumferential expansion, said front portion initially conforming to the normal three dimensional curvature of the figure and including extra material extending generally horizontally between, and being held at, the side seams at a level at which the user's body will increase its forward projection during pregnancy, said material being releasable progressively downwardly for the purpose of providing changes in the vertical curvature of the front but continuing to be held at the side seams, the circumferential and the vertical changes thereby permitting the garment to be changed in accordance with the changes in the curvature of the figure as pregnancy progresses.

9. A maternity garment comprising, in combination, a back, a front having at least a portion which is circumferentially expandable at least at the areas of the waist and abdomen, said front portion being joined to the back at side seams and comprising a single piece of material extending downwardly from the waistline over the abdomen, said means for controlling the circumferential expansion, said front portion initially conforming to the normal three dimensional curvature of the figure and including extra material below the waistline extending generally horizontally at the level at which the user's body will increase its forward projection during pregnancy and being held at the side seams at all times, said extra material being composed of a double layer of the material held together by spaced apart generally horizontal lines of stitches which are releasable in order to make the extra material releasable progressively downwardly for the purpose of providing changes in the vertical curvature of the front, the circumferential and vertical changes thereby permitting the garment to change in accordance with the changes in the curvature of the figure as pregnancy progresses.

10. A maternity garment comprising, in combination, a back, a front joined to the back at side seams, said front being formed of two portions which are joined together and comprise an upper portion which is circumferentially expandable at least at the areas of the waist and abdomen and a lower portion non-expandable circumferentially, releasable means for circumferentially expanding the upper portion substantially at the waist level, said upper portion extending below the abdomen and being gathered onto the upper edge of said lower portion, and a horizontally extending tuck between said waist level and upper edge of said lower portion formed by a line of stitches in the upper portion at a level at which the user's body will increase its forward projection during pregnancy, and a plurality of lines of stitches in the folded portion of the tuck, said stitches holding together the overlapped portions of the material forming the tuck and said stitches extending from side seam to side seam, the line of stitches forming the tuck and said plurality of lines of stitches being releasable intermediate the side seams.

11. A maternity garment comprising, in combination, a back, and a front having at least a portion which is circumferentially expansible at least at the areas of the waist and abdomen, said front portion being joined to the back at side seams, and said front portion at least at one level where the user's body will increase its forward projection during pregnancy including a generally horizontally disposed double layer of material extending across the front between the side seams and being held at said seams, and a plurality of spaced apart lines of stitches in said double layer, said lines of stitches extending from side seam to side seam and holding together the overlapped portions of the double layer of material, and at least one of said lines of stitches being releasable intermediate said seams.

12. A maternity garment comprising, in combination, a back, and a front having at least a portion which is circumferentially expansible at least at the areas of the waist and abdomen, said front portion being joined to the back at side seams, and said front portion at least at one level where the user's body will increase its forward projection during pregnancy including a generally horizontally disposed double layer of material extending across the front between the side seams and being held at said seams, a plurality of spaced apart lines of stitches in said double layer, said lines of stitches extending from side seam to side seam and holding together the overlapped portions of the double layer of material and at least one of said lines of stitches being releasable intermediate said seams, and code means for indicating the releasable lines of stitches.

13. A maternity garment comprising, in combination, a back, and a front having at least a portion which is circumferentially expansible at least at the areas of the waist and abdomen, said front portion being joined to the back at side seams, and said front portion at least at one level where the user's body will increase its forward projection during pregnancy including a generally horizontally disposed double layer of material extending across the front between the side seams and being held at said seams, a plurality of spaced apart parallel lines of stitches in said double layer, said lines of stitches extending generally horizontally and holding together the overlapped portions of the double layer of material, a curved line of stitches extending from one side seam to the other side seam and intersecting each of said parallel lines of stitches in two places, said parallel lines of stitches each being releasable intermediate the two intersections with said curved line of stitches.

14. A maternity garment comprising, in combination, a back, and a front having at least a portion which is circumferentially expansible at least at the areas of the waist and abdomen, said front portion being joined to the back at side seams, and said front portion at least at one level where the user's body will increase its forward projection during pregnancy including a generally horizontally disposed double layer of material extending across the front between the side seams and being held at said seams, said double layer being of substantially the same vertical measurement from side seam to side seam and including a plurality of spaced apart lines of stitches extending from side seam to side seam and holding together the overlapped portions of the double layer of material, said lines of stitches being individually releasable intermediate the

side seams to provide increased convexity to the front of the garment.

15. The garment of claim 1 wherein the separate releasable means includes a plurality of generally horizontally disposed double layers of material with the layers of each double layer being joined together intermediate the side seams by a plurality of lines of stitches which extend generally horizontally from side seam to side seam and hold together the overlapped portions of the double layer of material, said lines of stitches being individually releasable at the desired level to provide increased vertical measurement to the front of the garment.

16. The garment of claim 8 wherein said front is formed of a plurality of portions with the adjacent portions being joined together by a plurality of generally horizontally disposed curved lines of stitches which form a double layer of material extending horizontally across the front from side seam to side seam, the curved lines of stitches being in spaced relation to each other and being individually releasable intermediate the side seams.

17. The garment of claim 8 wherein the front is formed of a bodice portion and a skirt portion with said portions at their adjacent edges being cut with the grain of the goods and being secured together to provide a double layer of material by a plurality of lines of stitches which are spaced from each other and extend from one side seam to the other side seam in said double layer, said lines of stitches being individually releasable between said side seams and the deepest line of stitches corresponding to the normal curve of the waistline.

18. The garment of claim 8 wherein the front is formed of a bodice portion and a skirt portion with said portions at their adjacent edges being cut with the grain of the goods and being secured together to provide a double layer of material by a plurality of lines of stitches which are spaced from each other and extend from one side seam to the other side seam in said double layer, said lines of stitches coming to a substantially common point at each side seam and the deepest line of stitches being parallel to the grain of the goods.

19. The garment of claim 8 wherein the extra material comprises a horizontally extending tuck formed by a line of stitches across the front from side seam to side seam, and a plurality of other lines of stitches spaced apart in the folded portion of the tuck, said other lines of stitches holding together the overlapped portions of the material forming the tuck and being curved away from the line forming the tuck and extending from side seam to side seam, the line of stitches forming the tuck and the curved line of stitches being releasable intermediate the side seams.

20. The garment of claim 8 wherein there is a substantially horizontal tuck extending across said front portion below the waistline between the side seams, and wherein the extra material comprises a tuck formed behind said first mentioned tuck and concealed from view, said second mentioned tuck being releasable.

21. The garment of claim 8 wherein there is a plurality of larger tucks spaced from each other and extending substantially horizontally from side seam to side seam in said front portion, each larger tuck having concealed behind it a smaller tuck which comprises the extra material, each smaller tuck having a plurality of lines of stitches

in a folded portion of said smaller tuck for holding together the overlapped portions of the material forming the smaller tuck, the line of stitches forming the smaller tuck and the lines of stitches in the folded portion of the smaller tuck extending from side seam to side seam and being releasable intermediate the side seams.

22. The garment of claim 1 wherein said front is formed of a bodice portion and a skirt portion, said portions at their adjacent edges being cut with the grain of the goods and being secured together by a plurality of curved lines of stitches extending substantially horizontally from one side seam to the other side seam to provide vertically releasable means, and a plurality of horizontal tucks in the front below the waist level, one of said tucks being located substantially at the level at which the wearer will have the greatest forward projection during pregnancy, and smaller horizontal tucks concealed behind each of the tucks which are located below the waist level, said concealed tucks being releasable to provide additional vertically releasable means.

23. The garment of claim 8 wherein the front portion is adapted to extend below the abdomen and wherein there is a depending skirt portion which is formed of a piece of material separate from said front portion, said front portion being gathered and connected to said depending skirt portion below the abdomen, said dependent skirt portion being non-expansive circumferentially.

24. The garment of claim 8 wherein the extra material is in the form of a horizontal tuck of uniform vertical measurement extending across the front from one side seam to the other side

seam with the tuck being releasable intermediate the side seams.

5 25. The garment of claim 8 wherein the extra material is in the form of a seam formed of a plurality of lines of spaced apart stitches extending generally horizontally from one side seam to the other side seam, the deeper lines of stitches being releasable intermediate the side seams.

10 26. The garment of claim 8 wherein said extra material results from the front portion being formed of two pieces of material joined by a generally horizontal seam at the waistline, said two pieces at their joined edges having been cut with the grain of the goods and said seam having been 15 formed by a plurality of lines of stitches extending from one side seam to the other side seam, the lines of stitches including a line which is substantially parallel to the cut edges and a curved line of stitches spaced from the straight line and located farther from the cut edges than said 20 straight line of stitches.

JANET BRIGGS.
